SIMON F. STANTON, OF MANCHESTER, ASSIGNOR TO HIMSELF AND
JOHN M. STANTON, OF ALEXANDRIA, NEW HAMPSHIRE.

Letters Patent No. 85,867, dated January 12, 1869.

IMPROVEMENT IN BLIND-FASTENER.

The Schedule referred to in these Letters Patent and making part of the same.

To all whom it may concern:

Be it known that I, SIMON F. STANTON, of Manchester, in the county of Hillsborough, and State of New Hampshire, have invented a new and improved Blind-Fastener; and I do hereby declare that the following is a full, clear, and exact description thereof, which will enable those skilled in the art to make and use the same, reference being had to the accompanying drawings, forming part of this specification.

This invention relates to an improvement in fastening window-blinds, either closed or open; and

It consists in the construction and arrangement of parts as will be hereinafter more fully described.

Figure 1 represents the blind as open, and fastened back with my fastener.

Figure 2 is a vertical section of fig. 1 through the line *x x*.

Similar letters of reference indicate corresponding parts.

A represents the blind.

B is the window-frame.

C is the window-sill.

D is a semicircular bar, which is fastened to the window-sill at *e*, and to the frame or to the wall of the building at *f*.

It bows outward, so that the bottom rail of the blind passes over it at a point distant from the frame equal to the radius of the circle.

The top side of this bar is notched, as seen in the drawing, to receive the end of the vertical bolt, *g*, on the blind.

This bolt is attached to a back piece, *h*, which is screwed to the blind.

The bolt is secured to the back piece *h* by clips *i*, so that it can play freely up and down.

The back piece *h* has a projecting lug, *j*, and the bolt has another similar projecting lug or handle, *k*, by which it is raised when it is desired to adjust the blind.

Between the two lugs, *j* and *k*, there is a spring, *l*, which bears upon the lug of the bolt with a constant pressure, thus keeping the bolt in contact with the bar *D* at all times.

The bar *D* passes through the lower end of the bolt, thus supporting the blind, and holding the bar up to its true horizontal position.

When the blind is closed, the bolt will engage with the first notch, *o*, on the bar, and when it is fastened back, it engages with the last notch, *n*.

The intermediate notches are for holding the blind in any other desired position, or partially open.

It will thus be seen that the blind, by this arrangement, is securely fastened when entirely open, or partially open, and when entirely closed, and in such a manner that all movement of the blind is prevented until the bolt is raised, thus securing (among others) the advantage of fastening the blind securely when but partially opened.

I am aware of the patent granted to W. Patton, July 2, 1861, for an improved door and shutter-fastener, in which a bell-crank lever is employed, in connection with a notched semicircular bar; but this construction I do not claim.

What I claim as new, and desire to secure by Letters Patent, is—

The combination of the spring *l* with the angular back piece *h j* and the slotted angular slide *g k*, whereby the latter is held engaged with the notched semicircular guide *D*, constructed and arranged as shown and described.

The above specification of my invention signed by me, this 6th day of May, 1868.

SIMON F. STANTON.
